UNITED STATES PATENT OFFICE

EUGENE J. GUTMANN, OF CHICAGO, ILLINOIS

FLEXIBLE SHOE HORN

Application filed June 8, 1932. Serial No. 615,960.

The invention relates to shoe horns or similar articles and provides improvements over the shoe horns of ordinary rigid construction, the use of which is accompanied with more or less discomfort, such discomfort being especially noticeable in case the feet are sore or have tender spots on or adjacent the heel.

An object of the invention is the provision of an improved flexible shoe horn, the use of which enables shoes to be placed on the feet without discomfort.

Other objects of the invention include the provision of a flexible shoe horn which retains its shape throughout a long period of use, which is reversible and can be used equally well with either side in contact with the foot, and is so constructed that it functions satisfactorily for its intended purpose when not in exact position relative to the heel of the shoe.

A further object of the invention is the provision of a shoe horn which is simple, durable, economical and satisfactory for its intended purpose.

Many other objects and advantages of the construction herein shown and described will be obvious to those skilled in the art from the disclosure herein given.

To this end my invention consists in the novel construction, arrangement and combination of parts herein shown and described and more particularly pointed out in the claims.

In the drawing, wherein like reference characters indicate like or corresponding parts,

Fig. 1 is a plan view of a shoe horn illustrating one embodiment of the principles of the invention;

Fig. 2 is an edge view of the embodiment shown in Fig. 1;

Fig. 3 is a sectional view drawn to a larger scale of a fragmentary portion of the device shown in Figs. 1 and 2;

Fig. 4 is a plan view of an alternative embodiment of the invention comprising a single layer of flexible tough material such as raw hide which is compressed and permanently set to take the shape of a standard

shoe horn, the material having characteristics adapting it to retain its shape through frequent use for a long period of time; and

Fig. 5 is a longitudinal sectional view of the device shown in Fig. 4.

Referring now more particularly to the drawing, the numeral 10 generally designates a flexible reversible strip adapted for use as a shoe horn and embodying the principles of the invention. The strip 10 comprises outer plies or layers 11 of flexible material and an inner cushion layer 12. Any suitable flexible material constructed of either vegetable or animal fibre may be used for the outer layers 11 but animal fibre is in general preferred because of its greater flexibility. In practice the use of thin layers of fine leather for the outer layers 11 has been found highly satisfactory. In some cases the use of raw hide for one of the layers 11 and of leather for the other has been satisfactory and in still other cases the use of raw hide for both of the layers 11 has been found satisfactory as a shoe horn.

The inner layer 12 may consist of any suitable cushioning material such as a thin layer of soft rubber, the adjacent faces of the layers 11 and 12 being fastened together by adhesive material not shown. The outer fibrous layers 11 are preferably of the same or of approximately the same thickness, thereby adapting the article for reversibility or interchangeability of use, it making no difference which of the layers 11 is brought into contact with the heel.

The inner cushion layer 12 in combination with the soft flexible outer layers 11 provides a device adapted to be used comfortably with sore or tender heels and to conform to heels of all shapes and sizes.

The handle end 14 is preferably narrower than the main body 15 and contains an aperture 13 by means of which the shoe horn may be suspended from a hook or a nail if desired.

The main body 15 of the shoe horn has its lower end portion curved thereby adapting it to be positioned full depth in the shoe at any accidental angle or position and enabling the foot to be inserted in the shoe

without discomfort or danger of breaking the counter which cannot be done with the ordinary rigid shoe horn, it being necessary in the use of the latter to position it with 5 accuracy.

The invention also includes an alternative embodiment shown in Figs. 4 and 5 as comprising a single layer of raw hide or other animal or vegetable fibre having similar characteristics. The alternative embodiment takes the form of a shoe horn comprising a strip of raw hide 16 permanently fashioned to take the form of a standard shoe horn having an aperture 17 in 10 the handle portion.

The material, being flexible, adapts itself to any size or shape of heel and by reason of its yielding under pressure also avoids danger of tearing or breaking the 20 counter or heel of the shoe. Its flexibility adapts it for use as a shoe horn and enables the wearer to put on a shoe without discomfort and to remove the article from the shoe without injury to a sore or tender heel. 25 The flexibility of the material also causes the article to return to its original shape following temporary distortion caused by its compression between the heel of the wearer and the heel of the shoe.

30 The use of raw hide or of other similar animal fibre as shoe horn material enables the articles to be provided at a very low cost.

Thus it will be seen that I have provided 35 a novel flexible, reversible shoe horn, which is inexpensive to manufacture, which adapts itself to any size or shape of heel, which can be used with sore or tender feet without discomfort and which can be manufactured at a low cost.

Having thus described my invention, it is 40 obvious that various immaterial modifications may be made in the same without departing from the spirit of my invention; hence, I do not wish to be understood as 45 limiting myself to the exact form, construction, arrangement and combination of parts herein shown and described or uses mentioned.

50 What I claim as new and desire to secure by Letters Patent is:

1. As a new article of manufacture, an oblong reversible flexible strip having a configuration adapting it to be positioned in 55 the heel of a shoe with one end projecting therefrom to provide a handle, said strip comprising outer layers of fibrous material and an inner layer of cushioning material.

2. A shoe horn comprising three layers 60 of flexible material of similar configuration joined together to provide a flat strip, the outer layers being of fibrous material and the inner layer of cushioning material, the configuration of the strip adapting it to be 65 positioned in the heel of a shoe with one

end projecting therefrom to provide a handle.

In witness whereof, I hereunto subscribe my name this first day of June A. D., 1932.
